UNITED STATES PATENT OFFICE.

FRED A. REARDON, OF BRADFORD, MASSACHUSETTS, ASSIGNOR TO HAMEL SHOE MACHINERY COMPANY, A CORPORATION OF MASSACHUSETTS.

FOREPART-TURNING MACHINE.

Application filed April 9, 1919. Serial No. 288,706.

To all whom it may concern:

Be it known that I, FRED A. REARDON, a citizen of the United States, residing at Bradford, in the county of Essex and State of Massachusetts, have invented certain new and useful Improvements in Forepart Turning Machines, of which the following is a specification, reference being had therein to the accompanying drawings.

10 This invention relates to machines for turning the foreparts of shoes being of the general type disclosed in the patent to Eppeler, #706,038, August 5, 1902, in which a form is provided to receive the shoe, the heel of which has been previously turned, and cooperating turning elements are provided by means of which the sole is so manipulated on the form as to enable the operator to peel the shoe off the form by 15 hand, and over one of the elements right side out.

This invention provides various adjustments for rendering the machine more convenient to the operator and more satisfactory in operation with various grades and styles of shoes.

It also provides an improved form for supporting the upturned shoe and a cooperating turning implement therefor by 20 which the sole may be properly broken to facilitate the turning operation.

These and other objects and advantageous details of construction and arrangement of parts will be apparent from a more complete description of one embodiment of the invention disclosed in the accompanying drawings in which,—

Fig. 1 is a side elevation of the machine;

Fig. 2 is a partial vertical section on the line 2—2 of Fig. 1, looking toward the left;

Fig. 3 is a vertical section on the line 3—3 of Fig. 1, looking to the right;

Fig. 4 is a top plan view partly in section;

Fig. 5 is a fragmentary view partly in section showing the turning implements;

Fig. 6 is a detail of an adjustable stop;

Figs. 7 and 8 are fragmentary views illustrating various stages in the turning operation;

Fig. 9 is a partial side elevation showing a modified form;

Fig. 10 is a cross section thereof; and

Fig. 11 is a transverse cross section of the supporting form shown in Fig. 1.

The machine base A, of any suitable description, has carried thereon a vertically adjustable head B. Head B carries a base C in the form of a substantially T-section rod. At one end the base C is upwardly turned as at 1, and has pivoted thereon at 2 a sleeve member 3 provided with an inwardly extending abutment 4. A rod 5 is clamped at one end in sleeve member 3 by means of clamping bolt 6. Rod 5 extends 60 parallel to base C and at its other end passes through a sleeve 7.

A sleeve 8, provided at one end with a clutch face 9, is rotatably mounted on rod 5 and carries at opposite lateral sides bosses 10, 10^a on which is pivoted, by means of bolt 11, a yoke member 12 having an upwardly extending arm 13 and a horizontal arm 14 integral therewith. A sleeve 58, provided with a mating clutch face 59, is carried by 70 rod 5 and is adjustably secured thereto by a set screw 60. Arm 14 carries a depending link 15 which may be attached by a chain 16 or other suitable means, to a treadle 17 pivoted at 18 in the base A. 80

Sleeve 8 carries a bracket member 19 integral therewith and extending upwardly. It also carries a depending abutment member 20 provided with a set screw 21 adapted to contact with abutment 4 at certain times. 85 At its upper end bracket 19 is provided with a socket to receive one end of a turning implement 22 suitably fastened therein by a set screw 23. Pivoted to bracket 19 at 19' is a body abutment 24 in the form of a depending plate with a curved top portion. Member 24 is provided with a bracket 25, through which the pivot 19' passes, and which is further provided with a curved slot 26 through which a bolt 27, screwed into 90 bracket 19, may pass. Sleeved on turning implement 22 is a slide 28 having a slot 29 in the top face thereof in which a roll 30, mounted on pin 31 fast in implement 22, may play to allow member 28 to slide 95 lengthwise of implement 22 while preventing rotation thereon. A link 13^a is pivoted at one end to the arm 13, and at its other end to sleeve 28.

Pivoted at 29^a on member 28 is an auxiliary turning implement 30^a having an upwardly turned end 31^a provided with a roll 32. The other end of implement 30^a is downwardly inclined at 33, and has pivoted thereon a cam lever 34 having a cam roll 100 110

35 at its upper end. Between lever 34 and the end 33 is placed a compression coil spring 36 which urges roll 35 upwardly. Roll 35 cooperates with a cam member 37, 5 having a tang 38 projecting within a suitable opening in bracket 19, and made fast therein by a set screw 39.

At its opposite end base C is forked as shown at 40, 40^a, and between the forks 10 is pivoted a sleeve 41 on a pivot 42. Sleeve 41 has a depending sleeve 43, preferably integral therewith, through which is adapted to slide a rod 44 whose upper end enters the lower end of a boss 45 pivoted at 46 between jaws 47, 47^a integral with sleeve 7. A set screw operated by hand wheel 43' serves to retain rod 44 in any desired position. Also preferably integral with sleeve 7 are 15 two pairs of upstanding guide members 48, 20 48^a; 49, 49^a slidably carrying therebetween a plunger 50. An adjusting screw 51 passes down through a suitable portion of plunger 50 and engages at its lower end the rod 5. At its top, plunger 50 is provided with a 25 circular plate 51^a and centrally pivoted thereon, by means of a pin 52, is a turret member 53 having a series of substantially radial arms 54, which may receive projecting tangs of suitable forms such as 55, which 30 may be made fast therein as by set screws 56. By this arrangement a plurality of forms of varying shapes or sizes may be made readily available for use by the operator. Form 55 as shown, is of substantially 35 inverted teaspoon-shape having an upwardly curved longitudinal indentation 57 forming a concave lower face or substantially semi-ovoid form, within a substantially flat marginal portion. If desired, the 40 form may be provided with longitudinal corrugations as 57' on its upper convex surface, as shown in Figs. 9 and 10.

Passing up through a suitable opening in plate 51^a is a latch member 61 adapted to 45 engage in any one of a plurality of openings 62, in the lower face of turret 53 to retain any desired one of the forms 55 in substantial alignment with turning implement 22. Latch 61 may be retracted to release 50 the turret whenever desired by means of a link 63, connected to one arm of a bell crank 64, having a handle 65 on its opposite arm, and which is normally urged into a position to lock the turret by means of a 55 spring 66.

The operation of the machine is as follows: The mechanism carried by sleeve 8, including turning implements 22 and 30^a, is rocked to one side, as shown by dotted 60 lines in Fig. 2. The limits of rocking motion, which may be imparted to the sleeve, may be adjustably determined by the settings of sleeve 58 and set screw 21. A shoe, the heel of which has been turned, is then 65 placed over the form 55, the spoon-shaped

portion extending into the forepart. The turning implement 22 is then rocked upwardly into alignment with form 55 and the operator then depresses treadle 17. This serves to slide member 28 toward the form, 70 and roll 32 engaging the sole of the shoe thereon presses it upward into substantially the contour of the underside of the form, thus breaking the sole so that the turning operation is facilitated. The operator 75 then grasps the shoe near the heel and braces himself against the body abutment 24, and pulling towards him, peels the shoe from the form in its turned condition and over onto the turning implement 22, at the same 80 time allowing the auxiliary turning implement 30^a to retract out of the way.

During the turning operation the pressing of the sole upwardly into the concavity of the form serves to strain the upper over the convex surface of the form, whereby it is kept in proper position for turning without necessitating the employment of an auxiliary tool or device for keeping the upper 85 in smooth condition during the operation. The flat marginal portion of the lower face of the form causes the sole to be held substantially flat longitudinally, the breaking thereof preliminary to the turning operation being transverse, thus insuring an easier breaking action than if it were attempted to break the sole both longitudinally and laterally, and at the same time avoiding longitudinal distortion of the upper. 90 The corrugations on the form shown in Figs. 9 and 10 serve to decrease the contact area of the upper on the form and make more easy the peeling of the shoe therefrom. The turning operation with this mechanism leaves the sole crowned or bulged outwardly at the end of the drawing operation so that it is in condition for re-lasting 100 without further manipulation to effect the crowning, as has heretofore been found necessary. 105

For the purpose of adapting the machine to the requirements of the individual operator and different grades and styles of shoes the following adjustments may be effected. By loosening the hand wheel 43' and the proper set screws, rod 44 may be pushed upwardly, thus raising the end of rod 5 about the pivot point 2, thus changing the angle of the turning implement 22 and the form 57 to the horizontal. At the same time the body abutment 24 may be adjusted to substantially vertical position by means of the slot 26 and bolt 27, so as to be comfortable for the operator. Sleeve 7 may also be adjusted longitudinally of rod 5 to adjust the distance between the ends of implement 22 and form 57, in order to accommodate different thicknesses of stock and different styles of shoes as may be required. The turret 53 may also be adjusted vertically with 110 115 120 125 130

relation to the sleeve 7, by means of the adjusting screw 51. The following adjustments are seen to be possible with this construction. The machine may be adjusted vertically as a unit. Its angle to the horizontal may be adjusted. The body abutment may be adjusted. The form is adjustable independent of the other parts vertically and toward and away from the turning implement. The limits of the swing of the turning implement about rod 5 are adjustable in both directions. It is thus clear that the operator may adjust the machine to the most comfortable angles and positions for his individual requirements and also for different types of shoes to be operated upon.

Having thus described one embodiment of my invention, though it is evident that many changes might be made therein without departing from the spirit and scope of the invention, what is claimed is,—

1. A forepart form for shoe turning machines and over which the shoe is turned of substantially teaspoon shape.

2. A forepart form for shoe turning machines and over which the shoe is turned of substantially inverted teaspoon-shape.

3. In a shoe-turning machine, in combination, a forepart form adapted to enter the shoe to be turned and having an operative surface comprising a flat marginal portion and a concave portion within said marginal portion, and a turning implement separable therefrom to admit the shoe-sole between them and adapted to press the sole within said concave portion for arching the same.

4. A forepart form for shoe turning machines and over which the shoe is turned having a convex upper surface and a lower surface comprising a flat marginal portion and a concave portion within said marginal portion.

5. A forepart form for shoe-turning machines having a plurality of longitudinal corrugations thereon intermediate its opposite edges.

6. A forepart form for shoe-turning machines having a continuous operative surface from edge to edge and formed intermediate its edges with a plurality of longitudinal corrugations.

7. A forepart form for shoe turning machines of substantially spoon-shape and having corrugations on one side of the bowl thereof.

8. A forepart form for shoe turning machines provided with a convex upper surface having longitudinal corrugations thereon.

9. A forepart form for shoe turning machines of substantially inverted spoon-shape and provided with longitudinal corrugations on the convex surface thereof.

10. A forepart form for shoe turning machines having a shank and a bowl portion of

substantially semi-ovoid shape extending from one end of said shank.

11. A shoe turning machine having, in combination, members including a turning implement and a form, means for adjusting the angle to the horizontal of said members, a body abutment, and means whereby it may be adjusted angularly with relation to said members.

12. A shoe turning machine having, in combination, members including a turning implement and a form in substantial alignment therewith, means for adjusting the angle to the horizontal of said members, a body abutment, and means for adjusting said abutment into substantially vertical position for all the said adjustments of said members.

13. A shoe turning machine having, in combination, a turning element, an imperforate form in substantial alignment therewith, an auxiliary turning implement, and means for moving one of said implements whereby a portion thereof shall follow substantially the contour of said form.

14. A shoe turning machine having, in combination, an imperforate form having an upwardly-dished lower face and a turning implement arranged to bend the sole of a shoe to be turned while carried on said form to conform substantially to the curvature of said dished face.

15. A shoe turning machine having, in combination, an inverted spoon-shaped form, and a turning implement arranged to travel lengthwise of the bowl of said form and to yieldingly urge the sole of a shoe carried on said form to conform substantially to the curvature of the bowl.

16. A shoe turning machine comprising a forepart form constructed to hold the sole of a shoe carried thereby substantially flat longitudinally and provided with a convex portion engaging the upper of a shoe, and means for bending the sole laterally and simultaneously stretching the upper over said convex portion.

17. A shoe turning machine comprising, in combination, a support, a shaft fixed thereto, a turning implement rockably supported on said shaft and a forepart form carried by said shaft and adjustable lengthwise thereon in cooperative relation to said implement.

18. A shoe turning machine comprising, in combination, a support, a shaft pivoted thereto and adjustable angularly about said pivot, a turning implement rockably supported on said shaft, and a forepart form carried by said shaft and adjustable lengthwise thereon to cooperate with said implement.

19. A shoe turning machine comprising, in combination, a support, a shaft fixed thereto, a turning implement rockably sup-

ported on said shaft, and a vertically adjustable forepart form carried by said shaft and adjustable lengthwise thereon to cooperate with said turning implement.

5 20. A shoe turning machine comprising, in combination, a support, a shaft pivoted thereto and adjustable angularly about said pivot, a second support rockably carried on said shaft, a turning implement carried by 10 said second support, an angularly adjustable body abutment carried by said second support, and a forepart form carried by said shaft in cooperative relation to said implement.

15 21. A shoe turning machine comprising, in combination, a support, a shaft pivoted thereto and adjustable angularly about said pivot, a second support rockably carried on 20 said shaft, a turning implement carried by said second support, an angularly adjustable body abutment carried by said second support and a vertically adjustable forepart form carried by said shaft in cooperative 25 relation to said implement and adjustable longitudinally thereof.

22. A shoe turning machine comprising, in combination, a support, a shaft pivoted thereto and adjustable angularly about said pivot, a second support rockably carried on 30 said shaft, a turning implement carried by said second support, an angularly adjustable body abutment carried by said second support, and a turret for a plurality of forepart forms carried by said shaft.

23. A shoe turning machine comprising, in combination, a support, a shaft pivoted thereto and adjustable angularly about said pivot, a second support rockably carried on 35 said shaft, a turning implement carried by said second support, an angularly adjustable body abutment carried by said second support, a turret for a plurality of forepart forms carried by said shaft, and means to lock said turret in position to present any desired form into cooperative relation to 40 said turning implement.

In testimony whereof, I have signed my name to this specification.

FRED A. REARDON.
